US00D743017S

(12) **United States Design Patent**
Klochkov et al.

(10) **Patent No.:** **US D743,017 S**
(45) **Date of Patent:** **** Nov. 10, 2015**

(54) **LINEAR IONIZING BAR**(71) Applicant: **Illinois Tool Works Inc.**, Glenview, IL (US)(72) Inventors: **Aleksey Klochkov**, San Francisco, CA (US); **Peter Gefter**, South San Francisco, CA (US); **Steven B. Heymann**, Los Gatos, CA (US)(73) Assignee: **ILLINOIS TOOL WORKS INC.**, Glenview, IL (US)(***) Term: **14 Years**(21) Appl. No.: **29/443,821**(22) Filed: **Jan. 23, 2013****Related U.S. Application Data**

(63) Continuation-in-part of application No. 13/367,369, filed on Feb. 6, 2012, now Pat. No. 8,773,837.

(51) **LOC (10) Cl.** ..... **28-99**(52) **U.S. Cl.**USPC ..... **D23/366**(58) **Field of Classification Search**

Primary Examiner — Sandra Snapp(74) *Attorney, Agent, or Firm* — Uriarte Law**CLAIM**

The ornamental design for a linear ionizing bar, as shown and described.

DESCRIPTION

FIG. 1 is a perspective view of a linear ionizing bar showing our new design.

FIG. 2 is a rear elevational view thereof.

FIG. 3 is a front elevational view thereof.

FIG. 4 is a left side elevational view thereof.

FIG. 5 is a right side elevational view thereof.

FIG. 6 is a top plan view thereof; and,

FIG. 7 is a bottom plan view thereof.

1 Claim, 7 Drawing Sheets(56)
